DESIGN FOR A HANGING LAMP

Guy Montmartin, Paris, France

Application February 15, 1935, Serial No. 55,442
In France August 17, 1934

Term of patent 7 years

To all whom it may concern:

Be it known that I, Guy Montmartin, a citizen of the French Republic, residing at 113 Boulevard Malesherbes, in the Department of the Seine, in Paris, France, have invented a new, original, and ornamental Design for a Hanging Lamp, of which the following is a specification, due reference being had to the accompanying drawing, forming part thereof.

The single figure of the drawing illustrates a bottom perspective view of a hanging lamp, showing my new design.

The dominant feature of my design resides in the contour and general appearance of the globe used with my hanging lamp.

I claim:

The ornamental design for a hanging lamp, as shown and described.

GUY MONTMARTIN.
